DIRECT AND ALTERNATING CURRENT AMPLIFIER

Frank J. Bingley, Philadelphia, Pa., assignor, by mesne assignments, to Philco Radio and Television Corporation, Philadelphia, Pa., a corporation of Delaware

Original application November 23, 1935, Serial No. 51,324. Divided and this application July 5, 1939, Serial No. 282,934

14 Claims. (Cl. 179—171)

This invention relates to direct current amplifiers and particularly to wide band direct current amplifiers which will amplify with uniform gain frequency components ranging from zero to several megacycles such as is required in present television systems. Consequently, the invention is of particular application in such systems, although it will be understood, of course, that the invention is useful in any instance in which a direct current amplifier is required and particularly where the frequency range to be transmitted by the amplifier is extensive.

The principal object of the invention is to provide a means whereby direct coupling between amplifier stages may be obtained and where the deleterious effect of the capacity to ground inserted by such direct coupling, which would tend to by-pass high frequency components to be transmitted, may be avoided. In accordance with the invention, the signal to be amplified, which will include zero and high frequency components, is supplied to two channels by complementary frequency selective networks so that only the higher frequencies appear in the one channel and only the lower frequencies including zero frequency components appear in the other channel. Amplifier means are provided in each channel, the one being arranged to transmit the higher frequency components, whereas the other is arranged to transmit the lower frequency components, and then signals from each channel are re-combined.

This application is a division of my copending application Serial No. 51,324, filed November 23, 1935, now U. S. Patent No. 2,171,536, issued September 5, 1939, and the device described herein may be employed in the television system disclosed in said parent application to transmit both the brightness and the contrast signal described therein. The use of the invention is not, however, restricted to television systems.

The invention may be fully understood by reference to the accompanying drawing wherein:

Fig. 1 is a circuit diagram of a preferred form of the invention in which a multi-stage amplifier is illustrated.

Fig. 2 is a circuit diagram of another form of the invention; and

Fig. 3 is an illustration of the method of separating and re-combining the different signals of varying frequency.

In a conventional D. C. amplifier, the use of a blocking battery causes deleterious effects due to the capacitance of the battery to ground. As

will be seen from the following description, the present invention enables the use of such a battery without obtaining such deleterious effects.

In accordance with this invention, an exactly compensated equivalent D. C. coupled amplifier, which has a uniform gain vs. frequency characteristic over the entire video frequency range including zero frequency components and in which there is no phase distortion as between the input and output signals, may be made by dividing the amplifier stage into two branches: a conventional A. C. amplifier having the usual low frequency cut-off, and an additional D. C. coupled amplifier having a gain vs. frequency response complementary to the corresponding characteristic of the A. C. amplifier. By combining the outputs of the two amplifiers, substantially uniform gain over the entire frequency range is obtained.

Such an amplifier is shown in Fig. 1. This amplifier comprises two similar stages as indicated by the dotted line. The signal is applied to the network consisting of resistances R_1 and R_2 and condensers C_1 and C_2 . The A. C. coupled branch comprises tube V_1 , coupling condenser C_1 and grid leak R_1 . The conductively coupled stage comprises resistance R_2 , condenser C_2 and battery B_1 and the tube V_2 . The outputs of the two stages are combined in the common anode resistance R_3 .

The operation of this device is substantially as follows: The entire signal will appear across diagonal points X—Y of the network which points connect the network to the signal source and to ground through the battery B_2 . The portion of the total signal appearing across the resistance R_1 is supplied to tube V_1 , while the portion of the signal appearing across the capacitance C_2 , is applied to the tube V_2 . In both cases the amount of the total signal transferred will depend upon the ratio of the impedance across which the signal appears to the total impedance of the branch containing that impedance. Considering the branch supplying signals to tube V_1 , it will be noted that the impedance of the condenser C_1 will become infinite at zero frequency, consequently no unidirectional components will be transferred to this tube, but with increasing frequency, the impedance of C_1 will decrease and consequently at high frequency the total signal will be transferred by this tube. The signal transferred to tube V_2 on the other hand, is taken from across

the condenser C_2 , consequently, at zero frequency the entire signal will appear across C_2 but with higher frequency the amount of signal will decrease. In a preferred form of the invention the ratio of the impedance R_1 to the impedance of C_1 may be made equal to the ratio of the impedance of R_2 to the impedance of C_2 for such desired frequencies. This may be done by making the product R_1C_1 equal to the product R_2C_2 . Under these circumstances the voltage to ground at the point connecting R_2 and C_2 together will be complementary to the voltage at the point connecting R_1 and C_1 . Thus of the total voltage appearing across the diagonal, the part appearing across the one impedance will be transferred by one tube, the part appearing across the other impedance will be transferred by the other tube, and as these two parts when added together give the total input signal, obviously each may be amplified by the same amount and then added to give an amplified total signal.

It will be noted that the blocking battery B_1 may be used without the deleterious effects encountered in the use of such a battery in a conventional D. C. amplifier since the capacitance of the battery B_1 to ground is in shunt with that of the condenser C_2 and simply adds to it. It has been found that such an amplifier has a gain which may be independent of frequency over the video frequency range, that the output of the device will be similar in wave shape to the input even for transitory conditions and that there will be no phase distortion introduced.

A second stage similar to the one described may be coupled to the first stage as shown in Fig. 1. The corresponding elements of the two stages have been designated accordingly. Preferably the load resistance R_3 is small as compared with R_1 and R_2 as is necessary for wide band video amplification.

In Fig. 2, there is illustrated another form of the device which comprises four stages in the A. C. amplifier circuit and only two stages in the D. C. amplifier circuit. These stages are substantially identical with the corresponding ones of the preceding figure and the parts are correspondingly designated. The use of a lesser number of stages in the D. C. amplifier branch than in the A. C. amplifier branch is made possible by the fact that the gain per stage obtainable in the conventional video signal amplifier is relatively low due to the fact that low impedances must be used to minimize the effect of the capacity to ground of the customary blocking condensers, whereas this restriction does not apply to the D. C. compensator branch. Consequently, while it may be necessary to use, say four stages of A. C. amplification, as illustrated in Fig. 2, the same gain may be obtained in the D. C. compensator branch by the use of two stages as shown.

In Fig. 3, the gain vs. frequency characteristics are shown for the single and multi-stage amplifiers of Figs. 1 and 2. The solid line curves 1 and 2 are those of a single and multi-stage amplifier as in Fig. 1, the curve 1 being the curve of the A. C. amplifier stage, while the curve 2 is that of the D. C. compensator stage. It will be seen that the curve 2 shows rapidly decreasing gain until a cut-off point is reached at a relatively low frequency. This depicts in an exaggerated fashion the disadvantage of the D. C. amplifier as above mentioned, and is due largely to the

filter R_2C_2 , it having been pointed out above that the cut-off at relatively low frequency prevents amplification throughout any useful video signal range. In this case the cut-off is due to the condenser C_2 , however, in a conventional conductively coupled D. C. amplifier, the capacity to ground of the blocking battery would bring about the same result but at a higher frequency. It will also be seen that the curve 1 and the curve 2 are complementary so that a resultant curve 3 is obtained, which curve indicates that substantially uniform over-all gain is obtained throughout the video signal range. Due to the various stray capacities in the amplifier it will have the high-frequency cut-off common to all amplifiers which may, however, be made well above the video range by proper design.

When the device of Fig. 2 is employed, the A. C. amplifier branch exhibits a curve such as shown in broken-line representation at 4. It will be noted that this curve shows a reduction in gain over the range of lower frequencies as compared to the curve 1. The resultant curve 5 of curves 2 and 4, exhibits a slight reduction in gain at the lower frequencies. Inasmuch as this reduction in gain occurs at frequencies in the video signal range which are seldom encountered, the reduction is of little importance. In fact, this reduction may, in some instances, be desirable since it may be desired to diminish certain undesired signals at the frequencies in question. It is obvious that by suitably adjusting the gain of the D. C. amplifier branch, the gain at zero frequency, which is due entirely to the D. C. amplifier, may be made equal to the gain of the A. C. amplifier at high frequencies where the D. C. amplifier is substantially inoperative. It will be seen that the slight gain reduction at low frequencies represented in curve 5 may be charged, at least in part, to the low frequency attenuation introduced by the coupling elements $C_3 R_4$. This effect may be reduced, if desired, to almost any desired point through the proper choice of the relative values of R_3 , R_4 and C_3 , as related to the vacuum tube plate resistance, as well as by the values chosen for the elements R_1 , R_2 , C_1 and C_2 of the input network. It is apparent that the relative values of the elements in this input network determine the frequency at which the gains of the two amplifier branches are equal. The negative low-frequency gain of the A. C. amplifier as represented in the dotted curve 4 is intended to indicate that phase reversals, due for example to the reactive coupling elements between the tubes V_1 , may, at low frequencies, result in an A. C. amplifier output which is out of phase with the D. C. amplifier output. Thus, if at some low frequency the signal output of the A. C. amplifier is 180° out of phase with the output of the D. C. amplifier, the resultant gain will be proportional to the arithmetic difference or algebraic sum of the several outputs. Methods of computing the resultant gain where the phase difference is other than 180° are, of course, well understood in the art. It is understood that the curves in Fig. 3 are merely illustrative, and that in practice the characteristics may vary widely, depending upon the characteristics desired.

It will be understood, of course, that the invention is not limited to the specific forms herein disclosed but is capable of other forms of expression without departing from its scope.

I claim:

nal, one of said derived signals including said zero frequency components, means for amplifying said derived signal including said zero frequency components, means for amplifying said other derived signal comprising an amplifier having a plurality of stages, said amplifier having substantially uniform gain over the frequency range in which the derived signal comprises an appreciable portion of the said input signal, an output circuit, and means for combining said amplified signals in said output circuit.

8. In a signal amplifying system for amplifying signals from a source of signals having low and high frequency components, a plurality of channels including at least one amplifier in each channel, means in the input circuit of one of said amplifiers for providing a biasing potential, said means introducing inherent capacity to ground, a signal transfer network between said source and said channels, constructed and arranged to prevent by-passing of the high frequency components by said capacity, means for deriving from the said network a signal containing higher frequency components and for supplying the said derived signal to one amplifier, the said last-named means having a certain transfer frequency-response characteristic, means for deriving from the said network another signal containing the lower frequency components and for supplying the said other signal to the biased amplifier, the said second deriving mean having a transfer frequency response characteristic substantially complementary to the first-mentioned transfer characteristic, the two signal ranges being overlapping, and means for combining the two amplified derived signals.

9. In a signal amplifying system for amplifying signals from a source of signals having low and high frequency components, a plurality of channels including at least one amplifier in each channel, means in the input circuit of one of said amplifiers for providing a biasing potential, said means introducing inherent capacity to ground, a signal transfer network between said source and said channels, constructed and arranged to include said capacity as one of the elements of the network and thus prevent by-passing of the high frequency components by said capacity, means for deriving from the said network a signal containing higher frequency components and for supplying the said derived signal to one amplifier, the said last-named means having a certain transfer frequency-response characteristic, means for deriving from the said network another signal containing the lower frequency components and for supplying the said other signal to the biased amplifier, the said second deriving means having a transfer frequency response characteristic substantially complementary to the first-mentioned transfer characteristic, the two signal ranges being overlapping, and means for combining the two amplified derived signals.

10. In a signal amplifying system for amplifying signals from a source of signals having low and high frequency components, a plurality of channels including at least one amplifier in each channel, means in the input circuit of one of said amplifiers for providing a biasing potential, said means introducing inherent capacity to ground, a signal transfer network between said source and said channels, comprising a plurality of impedance elements arranged to provide a plurality of signal paths and including said capacity as one of the elements of the network, thus preventing by-passing of the high fre-

quency components by said capacity, means comprising one of said signal paths for deriving from the said network a signal containing higher frequency components and for supplying the said 5 derived signal to one amplifier, the said last-named means having a certain transfer frequency-response characteristic, means comprising another of said paths for deriving from the said network another signal containing the lower frequency components and for supplying the said 10 other signal to the biased amplifier, the said second deriving means having a transfer frequency response characteristic substantially complementary to the first-mentioned transfer characteristic, the two signal ranges being overlapping, and means for combining the two amplified derived signals.

11. In a signal amplifying system for amplifying signals from a source of signals having low and high frequency components, a plurality of channels including at least one amplifier in each channel, means in the input circuit of one of said amplifiers for providing a biasing potential, said means introducing inherent capacity to ground, a signal transfer network between said source and said channels, constructed and arranged to prevent by-passing of the high frequency components by said capacity, said network comprising a plurality of current paths 25 in shunt relation, at least two of said current paths comprising a plurality of dissimilar impedance elements in series relation, means for deriving from one of said paths a signal containing higher frequency components and for supplying the said derived signal to one amplifier, the said last-named means having a certain transfer frequency-response characteristic, means for deriving from the other of said paths another signal containing the lower frequency components and for supplying the said other signal to the biased amplifier, the said second deriving means having a transfer frequency-response characteristic substantially complementary to the first-mentioned transfer characteristic, the two signal ranges being overlapping, and means for combining the two amplified derived signals.

12. In a signal amplifying system for amplifying signals from a source of signals having low and high frequency components, a plurality of channels including at least one amplifier in each channel, means in the input circuit of one of said amplifiers for providing a biasing potential, said means introducing inherent capacity to ground, a signal transfer network between said source and said channels, constructed and arranged to prevent by-passing of the high frequency components by said capacity, said network comprising a plurality of current paths in shunt relation, at least two of said current paths comprising a plurality of dissimilar impedance elements in series relation, the ratio of the impedances of the elements of one path being substantially equal to the ratio of the impedances of the elements of the other path for all frequencies within the signal range, means for deriving from one of said paths a signal containing higher frequency components and for supplying the said derived signal to one amplifier, the said last-named means having a certain transfer frequency-response characteristic, means for deriving from the other of said paths another signal containing the lower frequency components and for supplying the said other signal to the biased amplifier, the said second deriving

means having a transfer frequency-response characteristic substantially complementary to the first-mentioned transfer characteristic, the two signal ranges being overlapping, and means for combining the two amplified derived signals.

13. A signal amplifying device comprising a source of input signals having frequency components within a predetermined range including zero frequency components, a first resistor and first capacitor serially connected in shunt with said signal source, a second capacitor and second resistor serially connected across said signal source, means for amplifying the signal voltage across said second capacitor, said signal voltage comprising the lower frequencies and the zero

frequency components of said predetermined range, additional means for amplifying the signal voltage across said first resistor, said last named signal voltage comprising the higher frequency components of said predetermined range, and means for combining said amplified signals in a common output circuit.

14. A signal amplifying device according to claim 13, wherein said first and second resistors and said first and second capacitors are related substantially in accordance with the formula

$$R_1C_1 = R_2C_2$$
